CLOTHES HANGER

Arthur G. Apy, 1308 Garden Drive,
Asbury Park, N.J. 07712

Filed July 17, 1967, Ser. No. 7,824

Term of patent 14 years

(Cl. D80—8)

Fig. 1

Fig. 2

Fig. 3

Fig. 4

I claim:

The ornamental design for a clothes hanger, substantially as shown.
